United States Patent Office

Des. 194,673
Patented Feb. 26, 1963

194,673

ADJUSTABLE CHAIR

Lee S. Watlington, 1204 Linden, Bloomington, Ill.

Filed Jan. 8, 1962, Ser. No. 68,232

Term of patent 14 years

(Cl. D15—3)

Fig. 1.

Fig. 2.

Fig. 3.

FIG. 1 is a perspective view of an adjustable chair, showing my new design, the opposite side being substantially the same;

FIG. 2 is a perspective view thereof to reduced scale of the chair shown in an adjusted position.

FIG. 3 is a rear elevational view thereof.

I claim:

The ornamental design for an adjustable chair, as shown and described.
